UNITED STATES PATENT OFFICE.

HENRY ARMSTRONG, OF ROCHESTER, NEW YORK.

SAW-VISE.

SPECIFICATION forming part of Letters Patent No. 635,907, dated October 31, 1899.

Application filed February 16, 1899. Serial No. 705,691. (No model.)

To all whom it may concern:

Be it known that I, HENRY ARMSTRONG, of Rochester, in the county of Monroe and State of New York, have invented certain new and useful Improvements in Saw-Vises; and I do hereby declare the following to be a full, clear, and exact description of the same, reference being had to the accompanying drawings, forming a part of this specification, and to the reference-numerals marked thereon.

My present invention relates to saw-vises, and particularly to that class adapted for holding circular saws while being sharpened or set, and has for its object to provide a means for supporting the saws and permitting their rapid insertion and removal and also their adjustment to bring the different portions into proper position, and, further, has for its object to provide a vise that is capable of adjustment to vary the angle of the saw relative to a horizontal plane, whereby the edges of the teeth may be readily sharpened at the proper angle.

To these and other ends my invention consists in certain improvements and combinations of parts, all as will be clearly described, and the novel features pointed out in the claims at the end of this specification.

In the drawings, Figure 1 is a front elevation; Fig. 2, a longitudinal sectional view on the line *x x* of Fig. 1; Fig. 3, a similar view showing the vise opened to receive a saw; Fig. 4, a sectional view on the line *y y* of Fig. 2; Fig. 5, a similar view on the line *z z* of Fig. 2.

Similar reference-numerals in the different figures indicate similar parts.

In the present embodiment of my invention I employ a vise adapted to be secured to a bench-top or other support and consisting of movable and stationary jaws 2 and 3, pivoted together by a pin 4 at their lower ends and having the plain engaging surfaces 5 upon their upper extremities, between which a saw-plate (indicated by 6) is secured. The jaws 45 are locked, engaging the saw, as described, by means of wedge-surfaces 14, formed on a block or slide 7, movable in guides 7^x on the jaw 2 and coöperating with the inclined surfaces of notches 50, formed upon each side of 50 the outer end of a stud or pin 8, adjustably

secured to the jaw 3 and extending through a slot or elongated aperture 9 in the jaw 2 to the front side of the vise.

10 indicates a handle, pivoted at 11 to the movable jaw and provided with a curved slot 55 12, open at the end, and in which latter is arranged a stud 13, connected to the lower end of the slide 7, carrying the wedges 14, said parts operating, as the handle is raised, to move the wedges out of engagement with the 60 pin and permit the separation of the jaws.

When a circular saw is placed in the vise, the pin 8 projects through the arbor-aperture at the center and supports the saw, with its teeth, above the edges of the jaws, and to accommodate saws of various diameters so that the teeth may always be supported at the proper height I provide an elongated slot 15 in the rear jaw, and upon the pin 8 are also provided guides 16 and a foot or extension 17, 65 adapted to slide in the slot and to coöperate with a clamping-screw 18, whereby the pin may be held in any desired position of adjustment. A slot 9 is provided in the front jaw 2, corresponding to the slot 15 in the stationary jaw, and a corresponding slot is formed in the slide 7, through which the stud projects, permitting the vertical movement of the wedges to clear the pin and allow the outer jaw to be tilted back upon the pivot 4, as 70 shown in Fig. 3, thereby permitting the ready removal or insertion of a saw.

In order that the saw may be held at an angle, so that the file may be held more nearly horizontal while sharpening the sides of 85 teeth—as, for instance, the teeth of crosscut-saws—I provide a pivotal connection between the bench or support and the rear side of the vise, consisting, preferably, as shown in the present instance, of a perforated lug or boss 90 formed upon the rear of the jaw 3, pivoted upon the pintle 20, extending through similar ears or lugs 21, formed upon a plate 22, which is adapted to be secured to the bench-top by screws or in any other suitable manner. 95 A pivoted link 23, pivoted upon a pin 24 between lugs 25 on the lower end of the vise, is adapted to extend beneath the support 1 and coöperate with a shoulder 26 and locking-nut 27 thereon, operating through a slot 28 in the 100

link, whereby the vise may be tilted to any desired position and secured by tightening the locking-nut.

In the vertical sectional views I have shown Fig. 5 an aperture 30, which may be provided in the rear jaw near its upper end to receive a pin or stud (shown in dotted lines, Fig. 2) and positioned to support circular saws smaller in diameter than those for which the larger sizes of vises are adapted.

The upper ends of the jaws are rounded to conform to the circumference of the saw, allowing several teeth to be sharpened at a single clamping; but the device could be adapted equally well for holding straight saws if the engaging ends of the jaws were formed straight across the top.

This device is particularly adapted to be made of cast-iron, and the parts being few and of simple construction very little labor is required in uniting them. The handle 10 is pivoted upon the pin 11, formed at the side of the movable jaw, and the latter has a lug or projection 31^x cast thereon to prevent the accidental removal of the handle; but a notch 31, formed in the handle at the side of the bearing, permits the handle to be applied or removed by bringing the notch into register with the lug, when the latter may be passed through the former, and the handle when in the normal position is held securely upon the pin. The open-ended slot 12 permits the easy removal of the handle from engagement with the pin 13 when the latter is raised into the vertical position.

The operation will now be readily understood. The jaws being separated, the saw is placed upon the pin 8, which is then adjusted vertically to bring the saw-teeth into the desired position, and secured by the clamping-nut 18. The handle 10, pivoted to the movable jaw, is raised, carrying with it the bearing-pin 13, moving the latter and the wedges 14 on the slide 7 vertically until above the pin, when the jaws may be closed, and by dropping the handle the wedges engage the notches 50 in the pin, locking the jaws and securing the saw.

By employing the wedges as a locking means I am enabled to greatly simplify the device, and by pivoting the handle in the detachable manner described the vise is capable of being packed into small compass and readily set up when desired for use.

It will be seen that the handle serves not only as an operating means for the locking mechanism, but also as a handle for opening and closing the movable jaw, and the same serves to operate both movements and allows the device to be manipulated quickly.

I claim as my invention—

1. In a vise, the combination with a stationary jaw and a movable jaw pivoted thereto, of an interlocking member arranged rigidly upon the first-mentioned jaw, and a locking member sliding upon the other jaw adapted to engage with the other member.

2. In a vise, the combination with a pair of pivoted jaws, of a pin secured to one of the jaws and having shoulders thereon, of a locking member sliding upon the other jaw and engaging the shoulders on the pin. 70

3. In a vise, the combination with a pair of pivoted jaws, of a pin adjustably mounted upon one of the jaws and having shoulders thereon, and a locking member sliding upon the other jaw and adapted to engage therewith.

4. In a vise, the combination with a pair of pivoted jaws, of a pin adjustably secured upon one of the jaws and having shoulders adapted to be engaged by a movable locking means carried upon the other jaw.

5. In a vise, the combination with a pair of jaws, of a pin adjustably secured to one of the jaws and having a shoulder thereon, of a movable wedge carried upon the other jaw and adapted to coöperate with the shoulder on the pin.

6. In a vise, the combination with a pair of pivoted jaws and a pin mounted upon one of the jaws and having shoulders thereon, of a plate having the wedges and sliding in ways upon the other jaw, and an operating-handle pivoted to the said jaw and connected to the plate.

7. In a vise, the combination with a stationary jaw and a movable jaw pivoted thereto, of a pin adjustable in a slot in the stationary jaw, and a corresponding slot in the movable jaw through which the pin projects, guides upon the latter jaw arranged at the sides of the slot, and a plate sliding therein.

8. In a vise, the combination of the two jaws pivoted together, one of said jaws having a pin adjustably secured thereto, a locking-plate movable upon and carried by the other jaw, and a wedge connection between said plate and pin.

9. In a vise, the combination of the two jaws pivoted together, one of said jaws having a pin rigidly secured thereto, a locking-plate movable upon and carried by the other jaw, a wedge connection between said pin and plate, and a handle connected to said plate for causing its operation and controlling the movement of the jaw.

10. In a saw-vise, the combination with the coöoperating jaws having the recesses or sockets near their upper ends for the reception of a removable pin, of an adjustable pin or saw-support extending between the jaws, and means for clamping the jaws.

11. In a vise, the combination of the stationary jaw, the adjustable pin thereon having the engaging projections at its end, the movable jaw having the longitudinal slot, the slotted plate sliding on the movable jaw, a wedge connection between the pin and plate, the handle pivoted on the movable jaw, and the slot-and-pin connection between said handle and sliding plate.

12. The combination with the jaws pivoted together, one jaw having the locking-pin

thereon extending through the other jaw, and the other jaw having the slot and the pivot-pin provided with the lug, of the locking-plate sliding on one jaw and having a wedge connection with the locking-pin, and a pivot-pin, the operating-handle having the slot in which the pin on the locking-plate projects, and the aperture through which the pivot-pin extends.
